IRONER ROLL RELEASE

John A. Castricone, Peoria, Ill., assignor to
 Altorfer Brothers Company, Peoria, Ill., a corporation of Illinois

Application January 13, 1938, Serial No. 184,821

11 Claims. (Cl. 38—61)

This invention relates to ironing machines, and more particularly to a roll release mechanism for oscillating ironer rolls.

In the present prevailing practice it is quite common to provide an ironing machine with an ironing bed in the form of a relatively long roll or cylinder adapted to cooperate with a heated ironing shoe and to be rotatably driven by an electric motor operating through any suitable reduction gearing. In some instances, a crank or eccentric is included in the driving connection in such a manner that the ironing roll is caused to oscillate rather than to rotate in order to facilitate the pressing operation on such garments that are not conveniently handled in a constantly rotating machine. When using such a machine, the operator customarily positions the garment upon the ironing bed or roll with a portion of the garment so positioned as to be engaged and pressed by the ironing shoe. It is then desirable that the operator be able to manually advance the roll in such a manner that other contiguous portions of the garment can be positioned under and pressed by the shoe, without the necessity of removing the garment from the roll.

In order to accomplish this result means must be provided whereby the roll may be completely disengaged from its oscillating mechanism when the machine comes to a stop, since such mechanisms are by their nature irreversible and if not disengaged serve to lock the roll against rotary movement whenever the machine is stopped. Furthermore, to be of any practical value the disengaging mechanism must be automatically operated when the ironing shoe is withdrawn from the roll, since the operator customarily uses both hands in guiding the garments and therefore cannot readily operate any additional manual controls.

It is, therefore, a primary object of this invention to provide an auxiliary release clutch whereby a movable ironer roll may be automatically disengaged from its power transmission during the idle periods of the machine, and thereby relieved of any locking action or frictional resistance present in the transmission in such a manner that the bed or roll may be free for manual movement by the operator.

Another object is to provide an ironing machine including a movable ironing roll, an irreversible power transmission means for automatically disengaging the roll from the transmission as the machine stops, and means for automatically

reengaging the transmission and the roll as the machine is started.

Another object is to provide an ironing machine having a roll releasing mechanism responsive to and synchronous with the movement of the driving motor control clutch.

Another object is to provide an ironing machine having a selective roll releasing mechanism such that it may be operated either manually or automatically at the will of the operator.

These and other objects are accomplished in the present invention, a preferred embodiment of which is illustrated in the drawings forming a part of the specification, in which:

15 Fig. 1 is a front elevational view of an ironing machine incorporating a preferred embodiment of the invention;

Fig. 2 is an end elevation of the right hand end of the ironing machine illustrated in Fig. 1;

20 Fig. 3 is an enlarged end elevation of the right hand end of the machine with certain parts broken away to show the driving mechanism;

Fig. 4 is an enlarged plan sectional view taken on the line IV—IV in Fig. 3;

25 Fig. 5 is a sectional view through the gear housing taken substantially on the plane of the line V—V in Fig. 4;

Fig. 6 is a detail plan sectional view of the driving mechanism taken substantially on the plane of the line VI—VI in Fig. 3;

Fig. 7 is a detail sectional view taken on the plane of the line VII—VII in Fig. 6;

Fig. 8 is a detail sectional view of the manual and automatic disengaging mechanism taken substantially on the plane of the line VIII—VIII in Fig. 4;

Fig. 9 is an enlarged fragmental end elevation of the gear housing with certain parts broken away to show the manual and automatic disengaging means;

Fig. 10 is a detail sectional view showing the control handle and index plate;

Fig. 11 is a front view of the gear housing certain parts being broken away to show the control mechanism;

Fig. 12 is a front view of the gear housing illustrated in Fig. 11 showing the control handle and index plate;

Fig. 13 is a detail sectional view taken on the line XIII—XIII of Fig. 12;

Fig. 14 is a rear elevation of the ironer roll and gear housing; and

Fig. 15 is a detail sectional view of the control handle and index plate illustrated in Figs. 9 and 10, but in a changed position.

The ironing machine here illustrated comprises in general an ironer roll 2 supported at one end by a standard or frame 3 upon a cabinet 4 and having a motor 10 to supply the power necessary to operate the various mechanisms. An ironing shoe 5 is supported upon a standard 6 mounted upon the cabinet 4 and is movable into engagement with the ironer roll 2. Whereas controls for controlling the operation of the machine are illustrated and will be described in conjunction with the parts controlled, the control switches for the motor itself and for the heating elements have not been illustrated, but may be assumed to be the standard devices usually employed for such purposes.

The shaft of the motor 10 may be coupled through any suitable coupling mechanism with a vertically mounted shaft 11 which finds bearing in a bearing member 12 carried on the housing 9. The upper end of the shaft 11 carries a worm 13 which at its upper end is journaled in a bearing 14 carried in a boss or projection 15 formed integral with or otherwise secured to the housing 9. The worm 13 engages and drives a worm gear 16 which is rotatably mounted upon a shaft 17 which at one end is carried in a bracket 18 secured to the housing member 9 and which at its other end is secured by a reduced portion 19 within a boss 20 on the housing 9. The shaft 17 is provided with an enlarged portion 22 which provides sufficient strength for it to act as a journal for a pinion 23 which is rotatably mounted thereon. The end of the pinion adjacent to the worm gear 16 is provided with a clutch member 24 adapted to be engaged with and to be disengaged from a clutch member 25 formed integral with or otherwise secured to the worm gear 16. A clutch operating member receiving groove 26 is provided between the teeth of the pinion 23 and the clutch member 24 for engagement of a forked clutch control member or arm 27 which, as will be described hereinafter, serves to shift the pinion longitudinally of the enlarged portion 22 of the shaft 17, in order to engage or disengage the clutch parts 24 and 25.

A member 28 formed with gear teeth 29 meshed with the teeth of the pinion 23 at one end and having an eccentric or cam 31 at its other end is rotatably mounted between hardened plates 32 and 33 on a stub shaft 34 secured in a boss 35 on the housing 9. An eccentric strap 36 surrounds the eccentric or cam 31 and forms part of a connecting rod 37 which is connected to a rocker arm 39 at its opposite end by means of a pivot pin 38.

The rocker arm 39 is pivotally mounted upon a stub shaft 41 secured in a boss 42 formed on the housing 9 and includes a segmental gear 43 formed integral therewith and adapted to mesh with a pinion 44. The pinion 44 carries a bushing 45 rotatably mounted upon a reduced end of a shaft 46 and is also rotatably mounted in a bushing 47 carried by a boss 48 on the housing 9. A cap 49 may be used to close the end of the boss 48 to form a seal for the bearing. The opposite end of the shaft 46 is rotatably supported in a bushing 51 secured to a bracket 52. This end of the shaft also carries a sprocket 53 which is secured thereto as by a set screw 56.

Spaced from the bushing 51 by a thrust collar 57 which is pinned on the shaft by means of a pin 54, is a pinion 58 which is freely rotatable on the shaft 46. Between the pinions 44 and 58 is a clutch collar 59 which is splined to the shaft 46 by a plurality of splines 61 and which at one

end is slotted as at 62 for clutching engagement with pins 63 rigidly secured in pinion 58. The opposite end of the clutch collar 59 is provided with a number of slots 64 adapted to engage with corresponding teeth 65 formed in the inner end of pinion 44. The splined portion of the shaft 46 is enlarged to provide a shoulder to position the pinion 58. The clutch collar 59 has an annular groove 66 within which a clutch shifter block 67 is disposed, the shifter block being pivotally mounted upon a pin 68 eccentrically secured to a flange stub shaft 69 rotatably mounted in a bracket 73 integral with a front plate 71 which is in turn supported by cap screws 70 threaded into the housing 9.

A pinion 74 is mounted on the stub shaft 69 between the front plate 71 and the bracket 73 and is secured thereon in any desirable manner.

A segmental gear 75 having an integral arm portion 77 is mounted upon a pivot pin 76 affixedly secured to the front plate 71 in such a manner that the segmental gear 75 meshes with the pinion 74. A connecting link 78 is carried by the pivot pins 79 and serves to transmit movement from the control crank 80 mounted upon the control shaft 81 to the arm 77 carried by the segmental gear 75 and thence to the pinion 74 in such a manner as to rotate the stub shaft 69, move the shifter block 67 and thus control the engagement or disengagement of the clutch collar 59. It will be seen that movement of the control crank 80 in one direction will operate the segmental gear 75 and cause rotation of the pinion 74, which in turn will shift the clutch collar 59 longitudinally of the shaft 46 to engage the pinion 44 or pinion 58 depending upon which connection is desired and the direction in which the control shaft 81 is moved. A spring pressed ball detent 82 is mounted in a drilled opening 83 in the front plate 71 and is adapted to engage notches 84 on the segmental gear 75 in such a manner as to maintain the gear 75 in any position at which it may be set.

Between the rocker arm 39 and the internal 45 end of the stub shaft 41 is a pinion 85 which is rotatably mounted on this shaft and held in place thereon by a thrust washer 86 in turn held in place by a cotter pin 87. The pinion gear 85 is arranged at all times to mesh with pinions 50 23 and 58, and the gear 29 likewise at all times is in mesh with pinion 23 regardless of whether the clutch members 24 and 25 are engaged or not.

When the motor is in operation driving the worm gear 16, and the clutch members 24 and 25 are engaged, the gears 23, 29, 43, 44, 58 and 85 will be in motion, although the shaft 46 may be motionless if the clutch collar 59 should be in a neutral position. If the clutch collar 59 be shifted to connect the shaft 46 with the pinion 44, the shaft 46 will be rocked back and forth, whereas, if the collar 59 be shifted to connect the shaft to the pinion 58, the shaft 46 will be rotated. The roll support 3 is of a cantilever form and is more clearly illustrated in Fig. 3. Intermediate of its length is a shaft 88 which carries a large sprocket 89 and a smaller sprocket 90. A chain 91 is trained over sprockets 53 and 89 and a chain 92 is trained over the other sprocket 90 on the shaft 88 and over the sprocket 93 which is connected with the roll 2 for driving the same. The arrangement is such that the roll 2 may be rotated in the direction of the arrow shown in Fig. 3 or may be oscillated. The bottom of the housing 9 is formed to provide an oil sump 75 within the depression 94 in which a small idler

gear 95 is mounted for rotation upon a shaft 96 secured in the housing 9. This idler gear is arranged to dip into a body of oil 97 carried in the sump and to carry the same to the worm gear 16 and thence to other moving parts, but as this mechanism and the bearing parts 12 form no part of the present invention, they will not be further described herein.

An element 98 is freely rotatable upon the shaft 17 and is arranged to be rotated between the position in which it is illustrated in Figs. 3 and 4 and a position 180 degrees removed therefrom. The inner end of the element 98 is provided with two transverse slots 99 and 101, which are substantially at right angles to one another. Within the slot 99 and pivotally mounted upon a reduced hub portion 110 of the member 98 is a latch operating member 102 having oppositely directed fingers 103 and normally urged in a counter-clockwise direction about the hub portion 110, viewing Fig. 7, by a tension spring 105 affixed between a post 106 on one of the fingers 103 and a post 107 carried by the element 98. Within the slot 101 and slidably mounted therein is a slide plate 108 which is slotted as at 109 to receive the pin 104 carried by the latch operating member 103. The plate 108 has an elliptical slot 111 through which the shaft 17 and the hub 110 freely pass and which is provided with a latch plate 112 at one end, the latch plate 112 being rigidly secured thereto in any convenient manner. The latch plate 112 has a tooth 113 adapted to be received in any one of a series of conforming depressions or notches 114 in a disk 115 secured to worm gear 16 for rotation therewith. The plate 108 retains the member 102 in its position and its slot 99, while the plate 108 in turn is secured in its position by cap screws 116.

A dog 117 carried by the lever 118 pivoted on the pin 119 is normally in the position shown in Fig. 7 where it serves to engage one of the fingers 103 and thus maintain the latch tooth 113 in inoperative position. This dog 117 will be released from the finger 103 when the lever 118 is moved about its pivot in the direction of arrow shown in Fig. 7, whereupon the spring 105 will swing the member 102 about its pivot to the opposite side of slot 99 from the position from which it is shown in Fig. 7, thereby causing the pin 104 to move the slide plate 108 to the left, and engaging the tooth 113 with one of the recesses 114 in the disk 115. The element 98 will then proceed to rotate with the gear 16 if this gear is being rotated.

The lever 118 is arranged to be operated through certain connections including a pull rod 121 and crank arm 122 secured on one end of a stub shaft 123 rotatably mounted in a boss 124 on the front plate 71; a crank arm 125 secured on the opposite end of shaft 123; and a pull rod 126 and lever 127 pivoted upon the cabinet 4 and pivotally connected to the pull rod 126 as at 129. In order to limit the movement of cranks 122 and 125 and thus the extent of movement of lever 118, the crank 125 is continued beyond the pivotal connection of the pull rod 126 where it is forked to provide projections 120 both of which are arranged to engage a stop 130 formed on the front plate 71. The lever 127 is arranged to be operated by the knee of the machine operator. It is intended that the lever 127 should be pushed by the operator only momentarily and only long enough to release the dog 117 from behind the tooth 103, whereupon the control

should be immediately released so that the dog 117 is free to engage a succeeding finger 103, having been returned to its original position immediately by the action of the tension spring 128 which may be secured between the lever 118 and a portion of the bracket 52. Thus when the element 98 has rotated 180°, the succeeding finger 103 will engage the dog 117 and through the medium of the pin 104 engaged with the walls of the slot 109 will move the tooth 113 out of engagement with the disk 115 and the element 98 will come to rest.

The outer end of element 98 is formed with an eccentric 131 about which an eccentric strap 132 is secured. At the high point of the eccentric and inwardly therefrom a cam surface 133 is formed, the purpose of which will shortly appear. The eccentric strap 132 may be formed integrally with a housing 134 for a spring 135, one end of which spring is arranged to abut against the tongues 136, struck from the housing 134. The rivet 137 may serve to hold the housing sides in position as well as to retain the end of the spring 135 in position. The opposite end of spring 135 bears against the pin 138 rigidly secured through and to the arms 139 of a forked crank member 141, fixed to a rock shaft 142 rotatably mounted in bearings 143 carried by a boss 144 on the housing 9. The rock shaft 142 extends out of the housing 9 and is journaled at its opposite end in a bearing 145 carried by a partition 146 in the rock shaft housing 140. A crank arm 150 is secured to this end of the rock shaft 142 and carries a connecting link 147 secured to the crank arm 150 by means of a pivot pin 148. The link 147 serves to connect the crank arm 150 to a swinging iron shoe supporting arm 149 pivotally mounted on the standard 6 by means of the pin 151. To this end the upper end of the link 147 is mounted on the cross pin 152 in such a manner that any counter-clockwise movement of the rock shaft 142 will operate through the crank 150 and the link 147 to rock the arm 149 about its pivot pin 151 and thus move the ironing shoe 5 into operative engagement with the ironing roll 2. The ironing shoe 5 is pivotally connected to the arm 149 by means of a pivot 153 in such a manner that the ironing shoe 5 may readily adjust itself and assume a proper position upon the roll 2.

In the operation of the ironing shoe actuating mechanism, just described, it will be apparent that when the operator moves the control lever 127 motion will be transmitted through the rod 126, crank 125, shaft 123, crank 122, rod 121 and lever 118 to the dog 117. As hereinbefore described, the movement of this dog 117 will release one of the fingers 103, engage the tooth 113 in one of the notches 114 in the element 115 and thus cause the element 98 to begin to rotate. This rotation will continue for 180° of movement at which time the dog 117 will engage the opposite finger 103, disengage the tooth 113 and thus stop the rotation of the element 98. At this time the eccentric 131 will have moved to its opposite position and withdrawn eccentric strap 132 and spring housing 134 from the position illustrated in Fig. 3. This movement will be effective to allow the pin 138 to move to the left, as viewed in Fig. 3, thereby rocking the rock shaft 142 and crank 150, and allowing the link 147 to move upwardly under the tension of the spring 154 until the adjustable stop member 155, which is secured to the link 141, contacts a lug 156 cast within the standard 6. The force exerted by the

spring 154 will, of course, be transmitted through the pin 152 to the arm 149 which will be caused to pivot about the pin 151 and raise the ironing shoe 5 away from the roll 2 in order to permit the removal of any garments being ironed, or the insertion of other garments between the roll 2 and the ironing shoe 5. In this connection it should be pointed out that the operation of the ironing roll 2 and of the ironing shoe 5 must be properly synchronized in such a manner that when the garment is placed upon the roll 2 and the control 127 is actuated, the roll 2 begins to rotate an instant before the ironing shoe 5 is moved into contact therewith, in order to prevent any possibility of scorching the fabric covering of the roll 2. In the same manner it is desirable that when the machine comes to the stop the ironing shoe 5 is withdrawn from contact with the roll 2 an instant before the roll 2 ceases its rotary movement.

In the present device this synchronization is accomplished by automatically disengaging the clutch elements 24 and 25 whenever the eccentric 131 carried on the element 98 moves into position to release the ironing shoe 5 from the roll 2 and by automatically engaging the clutch elements 24 and 25 at all times when the eccentric 131 operates to force the ironing shoe 5 and roll 2 into engagement. To accomplish this an arm 158 is mounted between a flange 159 and a sleeve 261 carried by a slidable shaft 262 mounted in a boss 263 of the housing 9 and urged outwardly therefrom by means of a compression spring 264. The clutch shifting arm 27 is locked to this slidable shaft 262 by means of the nut 265, and as hereinbefore described, this arm 27 rides in the slot 26 of the pinion 23 and is operative to slide the pinion 23 longitudinally of the shaft 17 in accordance with the movement of the slidable shaft 262. It will thus be seen that when the element 98 is released by the actuation of the control 27 and moves 180° from the position in which it is illustrated in the drawings the cam surface 133 will contact the arm 158 carried by a slidable shaft 262 and cause the shaft 262 to move inwardly in its bearings in the plate 52 and boss 263 against the action of the compression spring 264. The arm 27 will at this time shift the pinion 23 along the shaft 17 and allow the clutch elements 24 affixed thereto to disengage from the clutch elements 25 carried by the worm gear 16, thus disengaging the driving connection to the roll 2 simultaneously with the operation of withdrawing the ironer shoe 5 from the roll. It will be noted that this operation takes place in identically the same manner whether the clutch collar 59 is engaged with the pinion 44 or with the pinion 58.

When using an ironer of this type, it is highly desirable that when the machine is stopped and the ironing shoe is disengaged the ironer roll be free to rotate in such a manner that the operator may manually rotate the roll and thus advance a garment carried upon the roll further into engagement with the ironing shoe 5. This may be easily done when the clutch collar 59 is engaged with the pinion 58, since in this event the roll driving mechanism is completely reversible and when the roll is manually rotated its motion will be transmitted through the chains 93 and 91 to the shaft 61 and thence through the pinions 58 and 85 to the pinion 23. Since when the clutch elements 24 and 25 are disengaged the pinion 23 is free to rotate upon the shaft 17, it will be clear that there will be nothing within

the mechanism to resist the manual movement of the ironer roll 2.

In contrast to this it will be seen that the mechanism for oscillating the ironer roll 2 is irreversible, that is to say, it cannot be made to run backwardly and, therefore, characteristics inherent in the oscillating mechanism will act to prevent manual movement of the roll 2 even when the clutch elements 24 and 25 are disengaged. This is for the reason that when the clutch collar 59 is in engagement with the pinion 44 any movement transmitted from the roll 2 to the shaft 46 will be transmitted through the segmental gear 43 to the arm 39 and thence to the connecting rod 36 operating upon the eccentric 31. Any attempt to rotate the roll, therefore, can only be effective to move the eccentric 31 until it assumes its dead center position and thus locks the roll against manual rotation either forward or back.

The mechanism so far described is not new in the present application, having been disclosed and claimed in my co-pending application Serial No. 131,940, filed March 19, 1937, now Patent No. 2,115,941, issued May 3, 1938, but it is believed both necessary and desirable to show and describe the old structure in order to illustrate the need for and environment of the roll release mechanism to be hereinafter described.

When the driving mechanism is in its locked position it may be released by moving the selector lever 161, carried by the control shaft 81 into its vertical or neutral position. This motion will be transmitted through the shaft 81, crank 80, the link 78 and the arm 77 to the segmental gear 75 which will rotate the pinion 74 to the position shown in Fig. 8. In so doing the shifter block 67 will move the clutch collar 59 to a neutral position, such that the teeth 64 and 65 have disengaged without engaging the teeth 62 and 63. The shaft 46 is now free to rotate and since any manual force exerted on roll 2 will be transmitted to the shaft 46 by means of the chains 91 and 92, it will be clear that the roll 2 has been released from the locking effect of the eccentric 31 and may be moved backward or forward at the will of the operator.

The mechanism thus far described is, therefore, effective to release the roll, but for purposes of practical operation it is desirable that this releasing movement shall be automatically accomplished whenever the machine stops and the ironing shoe 5 disengages the roll 2, and that the driving mechanism be reengaged as the machine resumes rotation and the ironing shoe 5 again moves into engagement with the roll. To this end an index plate 162 is provided, having a sleeve 163 mounted in the boss 164 in the housing 9 and having a drilled opening 166 to accommodate the control shaft 81. A lug 166 is carried by the index plate 162 and is adapted to engage a notch 167 in the selector lever 161. The selector lever 161 is pivotally mounted on the control shaft 81 by means of a pin 168. It will be seen that moving the selector lever 161 into the position shown in Figs. 9 and 13 will cause the lug 166 to engage the notch 167 in the selector lever 161 and thereby lock the selector lever 161 to the index plate 162. However, the selector lever 161 may be pivoted to the position shown in Fig. 15 in which case the lug 166 and notch 167 will disengage and the index plate 162 may then oscillate independently of the manually movable selector lever 161.

A tooth 171 is provided on the sleeve 163 and

engages a notch 172 on a sleeve 173 journaled in the boss 164 and carrying the crank 170. A link 174 is pivotally connected to the crank 170 by means of the rivet 175 and extends downwardly to a rivet 176 carried by a lever 178 pivotally mounted on the stud 76, hereinbefore described. A ball 179 is mounted on a flange 181 carried by the lever 178 and is adapted to engage a drilled opening 182 in the boss 183 carried by the bell crank 184. The bell crank 184 is carried by and freely rotatable on the sprocket shaft 46 and is retained thereon by a collar 185 locked to the shaft 46 by means of a set screw 186. The opposite arm 187 of the bell crank 184 is perforated at 188 to receive a tie-rod 189 mounted on the eccentric strap 133 and secured thereto by means of a cotter pin 133. Washers 191 and a compensating spring 192 are carried by the tie-rod 189 and are secured in position thereon by means of cotter pins 193 and 194.

When the machine is being operated and the shoe 5 is engaging the roll 2, the parts will be in the position shown in Figs. 3 and 9. However, when the operator actuates the knee control 121, the eccentric 131 will rotate through 180° of movement and move the eccentric strap 132 toward the left (as viewed in Fig. 3) in order to disengage the ironing shoe 5 from the roll and stop the machine as hereinbefore described. At this time the tie-rod 189 will be moved to the left whereupon the cotter pin 193 and the washer 191 will engage the arm 187 of the bell crank 184 and rotate the crank 184 in a clockwise direction, moving the ball 179 and lever 178 upwardly and transmitting this upward movement through the link 174 and crank 165 to the sleeve 173. Since the sleeves 173 and 163 are locked together by the tooth and notch connection 171, 172, the index plate 162 will be caused to rotate in a clockwise direction (as viewed in Fig. 12). If the lug 166 carried by the index plate 162 is in engagement with the notch 167 in the selector lever 161, the selector lever will be moved from the dotted line position 161^a to the full line position, as shown in Fig. 12. As hereinbefore described, this movement will be effective to move the clutch collar 59 to its neutral position, thus disengaging the teeth 64 from the teeth 65 and releasing the roll 2 for free manual movement.

As the operator again actuates the knee control 121 to start the machine, the eccentric 131 will again rotate and move the eccentric strap 132 to the right (as viewed in Fig. 3) thus causing the ironing shoe 5 to move into engagement with the roll 2. At this time the tie-rod 189 will be carried to the right and will rotate the bell crank 184 in a counter-clockwise direction. This motion will, of course, be transmitted through the linkage just described to the index plate 162, causing the index plate to return to its original position, as shown in dotted lines at 162^a on Fig. 12, and since the index plate 162 and the selector lever 161 are locked together by means of the lug 166 and notch 167, the lever 161 will be returned to the position 161^a, as shown in Fig. 12. This action will move the teeth 64 of the clutch collar 59 into engagement with the teeth 65 carried by the pinion 44 and re-establish the driving connection between the eccentric 31 and the ironing roll 2. If the teeth 64 and 65 are not in their proper meshing relationship when the clutch collar 59 moves into engagement with the pinion 44, the movement of the tie rod 189 will be only effective to compress the compensating spring 192 until

such time as the teeth 64 shall move into meshing relationship with the teeth 65, whereupon the energy stored in the compensating spring 192 will act to move the bell crank 184 and the other related parts.

From the above it will be clear that when the selector lever 161 has been moved to a position 161^a in order to provide an oscillating drive for the ironing roll 2, the automatic control linkage 10 will be effective to return the selector 161 to its neutral position and thus release the roll 2 at any and all times when the machine is idle and the shoe 5 is not in engagement with the roll 2, and to return the selector 161 to its operative position 161^a and reestablish the driving connection whenever the clutch teeth 24 reengage the clutch teeth 25.

When it is desired to move the selector lever 161 from the oscillating position to the continuous rotating position, the selector 161 may be pivoted about the pivot 168 in such a manner that the lug 166 and notch 167 disengage. The selector 161 may then be moved to the dotted line position 161^b, as shown in Fig. 12. This movement will be transmitted through the control shaft 81 to crank 80, the link 78 and the arm 77 to the segmental gear 75, which will in turn drive the pinion 74 and move the shifter block 67, in such a manner that the clutch collar 59 will move toward the pinion 58 and engage the pins 63 by means of the tooth 62. The roll 2 will now be driven by direct gear drive and since this drive is fully reversible, there is no necessity of operating the automatic roll release mechanism, for the reason that while any manual movement of the roll 2 will be transmitted downwardly through the chains 92 and 91, the shaft 46, and the gears 58, 55, and 29, all of these parts rotate freely and will therefore offer no appreciable resistance to the manual movement of the roll 2. It should be appreciated, however, that while the gear drive illustrated in the present machine operates quite freely and therefore does not require a release clutch, the utility of such a construction is not necessarily limited to its use in connection with oscillating drives or irreversible mechanical movements, but may be advantageously applied in any case wherein the manual movement of the roll is resisted by elements within the transmission, whether such resistance arises from the inherent design of the movement, from friction, or from other causes.

While I have shown and described what is at present a preferred embodiment of the invention, I am aware that it is subject to numerous modifications without departing from the spirit and scope of the invention, and I therefore do not wish to be limited except as by the scope of the appended claims.

I claim:

1. In an ironing machine, a pair of relatively movable ironing elements comprising a rotatable roll and shoe, a motor for rotating said roll and relatively moving said roll and shoe into co-operating engagement, a clutch for disengaging said motor from said rotatable roll, a power transmission including an eccentric between said clutch and said rotatable roll, and means for disengaging the rotatable roll from the said power transmission whereby said rotatable roll may be free for manual movement.
2. In an ironing machine, a relatively movable ironing roll and shoe, a motor adapted to drive said roll and to urge said roll and shoe into co-operating engagement, a primary disengaging

clutch for said motor, an irreversible mechanical movement intermediate said primary clutch and said ironer roll, a secondary clutch intermediate said irreversible mechanical movement and said ironer roll, and automatic control means for said secondary clutch.

3. The combination, with a power transmission for mechanical ironers, of an eccentric, a primary clutch between said eccentric and a driving motor, a secondary clutch between said eccentric and an ironing roll, and mechanical means for simultaneously operating said primary and secondary clutches.

4. In an ironing machine the combination, with a power transmission including an oscillating mechanism adapted to convert rotary movement to oscillatory movement, of a driving motor; a primary clutch between said transmission and said driving motor, manually actuated clutch control means for said primary clutch, a secondary clutch between said transmission and an ironing roll, manually actuated control means for said secondary clutch, and mechanical means for simultaneously operating said primary and secondary clutches.

5. A driving mechanism for ironers and the like including a motor; a rotatable ironing roll, a power transmission including an eccentric, means for intermittently driving said power transmission and an automatic auxiliary clutch effective to engage said driven ironing element with said power transmission when the transmission is being driven and to disengage the ironing roll from the transmission when the transmission is idle.

6. In an ironing machine, an ironing roll, an oscillating mechanism for said roll whereby said roll may be moved in to-and-fro partial rotations, a driving motor for said oscillating mechanism, means for disengaging said driving motor from the oscillating mechanism, and automatically operating clutch mechanism adapted to disengage said ironing roll from said oscillating mechanism whereby said ironing roll may be free for manual movement and relieved of frictional resistance to such movement inherent in said oscillating mechanism.

7. In an ironing machine, an ironer roll, a power transmission including an oscillating mechanism whereby said ironer roll may be driven in successive to-and-fro partial rotations, a driving motor, a manually controlled clutch intermediate said driving motor and said oscillating mechanism, a secondary clutch intermediate said ironing bed and the oscillating mechanical movement whereby said ironing roll may be released from mechanical connection with said oscillating mechanism and relieved of mechanical resistance inherent in said oscillating mechanism, and automatic control means for said secondary clutch.

8. In an ironing machine, an ironer roll, a power transmission including an oscillating mechanism for moving said roll in to-and-fro partial rotations, intermittent driving means for said transmission, clutch means intermediate said ironer roll and said power transmission, and control means for said clutch, said control means being responsive to the movement of the power transmission to release said roll from mechanical resistance to movement caused by said transmission, and permit free manual movement.

9. In an ironing machine, an ironer roll; a co-operating ironing shoe; a motor; a clutch; manual control means for said clutch; rotary power transmission means adapted to be driven by said motor and to impart rotary movement to said ironer roll at certain times during the operation of the machine; oscillatory power transmission means adapted to be driven by said motor and to impart successive to-and-fro partial rotations to said ironer roll at certain times during the operation of the machine; a selector clutch whereby driving connection may alternately be established between either of said power transmission mechanism and said ironer roll to impart either constant rotary movement or oscillatory movement to said ironer roll; and means responsive to the operation of aforementioned manual clutch control means to move said selector clutch to a neutral position such that said ironer roll will be disengaged from mechanical connection with either of said power transmission mechanisms, and free from manual rotation.

10. In an ironing machine, an ironing roll, an ironing shoe cooperatively associated with said roll, roll operating mechanism for rotating said roll continuously in one direction or for effecting successive to-and-fro partial rotations of the roll while said roll and shoe are maintained in given position with respect to each other, a selective control for effecting either said continuous rotation or said to-and-fro partial rotations, and means for automatically disengaging said roll from said roll operating mechanism whereby said roll may be free for manual movement during the idle periods of the machine.

11. In an ironing machine; the combination, with a feeding and presser roll and cooperatively mounted ironing shoe, of pressure mechanism for moving said roll and shoe into cooperative engagement and releasing said roll and shoe from engagement; driving mechanism for rotating the roll continuously in one direction or in to-and-fro partial rotations, and automatic clutch means responsive to the operation of said pressure mechanism for disengaging said roll from said driving mechanism whereby said roll may be free for manual movement during the idle periods of the machine.

JOHN A. CASTRICONE.
